UNITED STATES PATENT OFFICE

125,608

DESIGN FOR A COSMETIC CONTAINER OR SIMILAR ARTICLE

Marie Comstock, Chicago, Ill.

Application December 21, 1940, Serial No. 97,513

Term of patent 7 years

To all whom it may concern:

Be it known that I, Marie Comstock, a citizen of the United States and residing in Chicago, in the county of Cook and State of Illinois, have invented a new, original, and ornamental Design for a Cosmetic Container or Similar Article, of which the following is the specification, reference being had to the accompanying drawing, forming a part thereof.

On the drawing:

Fig. 1 is a perspective view of a cosmetic container or similar article showing my new design; and

Fig. 2 is a top plan view thereof.

I claim:

The ornamental design for a cosmetic container or similar article, substantially as shown.

MARIE COMSTOCK.
